UNITED STATES PATENT OFFICE.

JAMES B. WHITAKER, OF LORETTA, VIRGINIA.

BOOK-SUPPORT FOR WRITING-DESKS.

SPECIFICATION forming part of Letters Patent No. 276,514, dated April 24, 1883.

Application filed February 19, 1883. (No model.)

To all whom it may concern:

Be it known that I, JAMES B. WHITAKER, of Loretto, in the county of Essex and State of Virginia, have invented certain new and useful Improvements in Book-Supports for Writing-Desks; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a desk provided with my improved book-support, and Fig. 2 is a top view of one of the frames.

Similar letters of reference indicate corresponding parts in both the figures.

My invention has relation to book-supports for writing-desks; and it has for its object to provide adjustable supports for one or two books upon a writing-desk, whereby a person may have both books in any desired position to each other for the convenience of the person reading or writing in the books, or comparing the books, or entering from one book into another; and it consists in the improved construction and combination of parts of the same, as hereinafter more fully described and claimed.

The frames upon which the books are placed, and which are adjustably fastened upon the desk, consist of two side bars, A A, having three or more slots, B, in which the ends of three cross-pieces, C C and D, slide. The middle cross-piece, D, is flat at both ends and round at the middle, while the upper and lower cross-pieces, C, are preferably flat through their entire length, so that the side bars may be slid in and out upon them, according to the width of the book placed upon the frame, they being provided with two pivoted arms, E, upon their upper sides near the middle, which serve to hold the edges of the leaves down, keeping the book open.

The lid of the desk is provided with a slide 45 or way, F, having inward-turned flanges G, in which slides an upright, H, having side-ward-extending flanges I at its lower end, which extend under the flanges G of the way, while its upper end is provided with a trans- 50 verse perforation, J, in which the central round portion of cross-piece D of one of the frames slides and turns, and in which it may be se- cured in any of its positions by a thumb-screw, K. An upright, L, having a similar perfora- 55 tion, M, and thumb-screw N for the reception and adjustment of the middle cross-piece of the other frame, is removably pivoted upon the upper part of the desk, it being preferably passed through perforations in the top and 60 bottom of the desk, in which it turns. By this arrangement and construction of the frames it will be seen that one book may be placed upon the upper frame, and be held in any desired position while its contents are compared with 65 or entered into the book upon the lower frame, which likewise may be adjusted in any desired position, and that the upper frame may be turned around upon its pivot, so that access may be had to it from the other side of the 70 desk.

Having thus described my invention, I claim and desire to secure by Letters Patent of the United States—

In a writing-desk, the combination of the 75 side pieces, A, having pivoted arms E and slots B, flat cross-pieces C, middle cross-piece, D, uprights H and L, having transverse perforations J and M, and the desk having way F in its lid, as and for the purpose shown and 80 set forth.

In testimony that I claim the foregoing as my own I have hereunto affixed my signature in presence of two witnesses.

JAMES B. WHITAKER.
